Primary Examiner — Catherine Ho(74) *Attorney, Agent, or Firm* — Lewis Kohn & Walker LLP; David M. Kohn; Kari Moyer-Henry(57) **CLAIM**

We claim the ornamental design for a customer assistance stand, as shown and described.

DESCRIPTION

FIG. 1 is a perspective view of a customer assistance stand, showing our new design;

FIG. 2 is a front view thereof;

FIG. 3 is a side view thereof;

FIG. 4 is a top view thereof; and,

FIG. 5 is a perspective view of a customer assistance stand shown in an environment of use.

The broken line portion of the figure drawings is included to show environment that forms no part of the claimed design.
